TRUSTEE, OF OAKLAND, CALIFORNIA.

METHOD OF PREPARING LIQUID FUELS FOR COMBUSTION.

Application filed March 1, 1923. Serial No. 622,103.

This invention relates to a method of preparing liquid fuels, such as hydrocarbon oils, and particularly low gravity crude oils, for combustion, the present application being an improvement over my copending application entitled "Method of preparing liquid fuels for combustion", filed August 23, 1921, Serial No. 494,658.

The object of the present invention is to generally improve the method or process described in my copending application. I accomplish this by first mixing oil, water and air to form an emulsion. I secondly subject the emulsion to a fairly low pressure. Third, the emulsion under pressure is again subjected to an emulsifying action. Fourth, it is then subjected to high pressure; and fifth, it is finally projected into a chamber maintained under comparatively low pressure. The method of emulsifying the fuel, subjecting the emulsion to low pressure, again mixing or further emulsifying the fuel and subjecting it to high pressure, and its final release and expansion before combustion, will be more fully described, having reference to the accompanying drawings, in which—

Fig. 1 is a plan view of the apparatus employed.

Fig. 2 is a side elevation of the same.

Fig. 3 is a vertical cross section on line 3—3, Fig. 1.

Fig. 4 is a vertical cross section on line 4—4, Fig. 1.

Fig. 5 is a detail view of the by-pass valve.

Referring to the drawings in detail, and particularly to Figs. 1, 2, 3 and 4, A indicates in general a high pressure pump which is divided into two sections as indicated at B and C. The section B consists of three cylinders, the pistons of which operate in unison, and the section C consists of three cylinders, the pistons of which operate in successive order, that is, the pistons are driven by a crank shaft and the cranks are set 120° apart, while the cranks operating the pistons and the cylinders B are set in alignment. The cylinders are supported in a base or frame D in any suitable manner and the crank shaft 2 is supported by three uprights or columns 3, in which are formed suitable bearings for its reception. Each

cylinder is provided with a piston as indicated at 5 and each piston is connected with its respective crank through means of a connecting rod 6. Oil is delivered to the cylinder of the first unit B, which is indicated at 7, water to the cylinder 8, and air to the cylinder 9, the pipes delivering the oil, water and air being indicated at 10, 11 and 12, respectively.

Interposed between the pipes 10, 11 and 12, and their respective cylinders, are valve cages such as indicated at 13. These cages are all identical in construction and the description of one will, therefore, suffice. The arrangement of the valves in the cages 13 is perhaps best illustrated in Fig. 3. There are two valves in each cage and they are nothing more or less than ordinary types of check valves which operate intermittently. The oil delivered by the pipe 10 passes the check indicated at 14 and as such enters the main passage 15, which is in communication with the cylinder chamber. Mounted in the passage and transversing the same is a second check 16 which serves the function of normally closing communication between the passage 15 and an auxiliary passage 17. This auxiliary passage is connected with a common main indicated at 18 and this is in turn connected with a by-pass valve 19 through means of a pipe 20, which will hereinafter be described.

Arranged on the discharge side of each of the cylinders 7, 8 and 9, are identical valve cages, as indicated at 21. These valve cages also carry two checks, but these checks seat in the same direction, that is oil admitted to the cylinder 7 passes through the check 14, the passage 15, and enters the cylinder 7 during the upward stroke of the piston. This oil discharges through the cage 21 during the downward stroke as the check valve 14 closes and the check 16 normally remains closed. The oil will, therefore, necessarily discharge through the cage 21 and as such passes through a check valve 22 and enters a chamber 23. It passes from said chamber through a by-pass passage 24 and enters a second chamber 25. It then passes through a check valve 26 and finally discharges into a common main indicated at 27, from where it is delivered to a mixing chamber generally indicated at E, and it is discharged

from the mixing chamber through a pipe 28 and again enters a common main indicated at 29, from where it is delivered to the successive cylinders of the unit C, as will 5 hereinafter be described.

So far the flow of oil through the cylinder 7 has only been described, but I wish it understood that the flow of water and also the flow of air is the same as the pistons in 10 the respective cylinders operate in unison. Hence, it will be seen that the cylinder 7 discharges a predetermined quantity of oil into the main 27, the cylinder 8 a predetermined quantity of water, and the cylinder 9 15 a predetermined volume of air. These predetermined volumes of oil, water and air enter and mix in the main 27 and a partial emulsion is here formed. This emulsion is delivered to the mixing chamber E, which 20 contains a series of fine screens, such as shown at 30. A substantially complete emulsion is here formed which is discharged through the pipe 28 and delivered to the second main indicated at 29 which connects 25 with the second pumping unit indicated at C. The emulsion formed in the mixing chamber E and carried by the pipe 28 and the main 29 is subjected to a fairly low pressure, in most instances not exceeding 100 30 pounds per square inch, and it is delivered under this pressure to the respective cylinders of the second pumping unit as will now be described.

The cylinders in the second pumping unit 35 are indicated at 31, 32 and 33. These cylinders are identical and have the same area, stroke and capacity. Duplicate or identical valve cages are employed in connection with each cylinder and the description of one 40 will, therefore, suffice. There is a valve cage located on the intake side of each cylinder which is generally indicated at 34, and there is a valve cage located on the discharge side of each cylinder generally indicated at 35.

45 The valve cages 34 and 35 are identical and in fact are identical with the valve cage indicated at 21, the only difference being that one valve cage is reversed with relation to the other as shown in Fig. 4, that is, referring to Fig. 4, the emulsion delivered to the second main 29 enters the cylinder 31 through the cage valve 34, that is, it first enters a chamber 36, then passes by a check valve 37 into a chamber 38. It is transferred from this chamber through a by-pass passage 39 into a chamber 40 and passes from this chamber into the cylinder 31 through a check valve 41. The emulsion enters during the upward stroke of the piston and is discharged through a discharge port 42 during the downward stroke as the check valve 41 closes. The emulsion thus discharging enters a chamber 43 in the cage valve 35. It then passes a check valve 44 and enters a chamber 45 from where it is 50 transferred through a by-pass passage 46 into a chamber 47. The emulsion passes from this chamber past a check valve 48, and then discharges into a third main generally indicated at 50. The combined capacity of the three cylinders indicated, at 55 31, 32 and 33, is equal to the combined capacity of the cylinders indicated at 7, 8 and 9. A uniform flow or continuous movement of the emulsion is thus maintained and the pressure is stepped up or increased when the emulsion discharges from the respective cylinders 31, 32 and 33 of the second unit, the pressure in some instances exceeding 3000 60 pounds or more per square inch, this pressure being obtained when the emulsion is discharged into the third main indicated at 50, and the pressure is maintained on the emulsion until it is discharged through an expansion valve or spray nozzle generally indicated at 51. This valve may be of any suitable construction, and may, for instance, represent the spray valve of an internal combustion engine. The valve would be intermittently opened and closed in such an instance and in other instances may remain continuously open, for instance, when injecting the emulsion into the furnace chamber of a boiler or otherwise, the capacity of the combined pumping units indicated 65 at B and C is more than sufficient to take care of the maximum amount of fuel required for any particular installation. It is, therefore, necessary to provide means for by-passing a certain amount of the fuel and recirculating the same through the pumping units as the maximum capacity of the pumping units is seldom required or employed.

To permit such recirculation and to maintain a constant and uniform high pressure in the main 50 and the pipe 52 with which the spray nozzle 51 is connected, the by-pass pipe 20 and the valve 19 are employed. The by-pass valve is perhaps best illustrated in Fig. 5. This valve is also a check valve inasmuch as the valve which is indicated at 53 is normally maintained on its seat by means of a spring 54. The tension of this spring is adjusted by means of a screw 55 or a similar device and as such makes it 70 possible to retain the valve 53 on its seat until a predetermined pressure is reached. The moment this pressure which, for instance may be 3000 pounds, is reached the valve opens and the emulsion delivered to the pipe 52 will enter the intake port 56 of the valve and then discharges through the port indicated at 57, which connects with the by-pass pipe 20. This pipe is in turn connected with the return main indicated at 18, and as the mixture enters the main under high pressure, it is obvious that the check valves 16 connected with the respective cylinders 7, 8 and 9, will open and that the return fuel will 75 be equally distributed to these three cylinders.

ders, to be again recirculated throughout the system as previously described.

- By generally reviewing the pumping unit here illustrated, it will be seen that means are provided for mixing two, three or more liquids under pressure, this means being illustrated by the cylinders indicated at 7, 8 and 9, the valve cages 21, the main 27, and the mixing chamber E. Means are also employed for the purpose of subjecting this emulsion to a low pressure, the means employed being the same pumps already specified. Means are then employed for increasing the pressure on the emulsion and for maintaining the pressure until the emulsion is liberated by the spray or expansion valve employed. Means are also employed for recirculating the emulsion when predetermined pressures are reached.
- 10 The valve cages indicated at 13 serve only two functions, to-wit: that of primarily admitting the oil, water and air employed, and secondly, that of re-admitting any liquid bypassed by the valve 19. The valve cages indicated at 21 serve only one main function, to-wit, that of preventing liquid under pressure from re-entering the cylinders during the suction stroke of the pistons or plungers. The valve cages indicated at 34 and 35 serve two functions, to-wit, that of mixing or further emulsifying the fuel, and secondly, that of preventing back-pressure or leakage through the cylinders, that is, the oil, water and air delivered to the first main indicated at 27 are more or less mixed the moment they combine in the main. They are further mixed when passing through the screens of the mixing chamber E and they are still further mixed during their passage through the valves indicated at 34 and 35 and the cylinders 31, 32 and 33. In other words, a mechanically perfect mixture or emulsion is obtained when the liquid finally enters the main indicated at 50 and as it is subjected to an exceedingly high pressure at this point, the emulsion is maintained and the fuel remains as an emulsion until discharged. It might here be stated that the fuel oil and the water are impregnated with the air. This is of great importance as the main features of the present invention are, first, that of forming an emulsion of a liquid fuel with water and air, or with some other expansible medium; secondly, subjecting the emulsion to high pressure, in this instance 3000 pounds or more, and then instantly lowering the pressure before combustion by projecting the emulsion into a chamber maintained under comparatively low pressure. Such a chamber may, in some instances, be represented by the cylinder of an internal combustion engine and, in other instances, represented by an ordinary furnace box such as used in connection with boilers and the like.
- 55 What actually happens during the opera-

tion of the pumping units is as follows: Oil, water and air in predetermined proportions are simultaneously delivered to the main indicated at 27, where they commingle to form a preliminary emulsion. This emulsion is practically completed when the mixture passes through the screens of the mixing chamber E and when subjected to the fairly low pressure previously specified. The quality of the emulsion is, however, increased during its passage through the valve cages 34 and 35 and the respective cylinders 31, 32 and 33, and it is further increased or improved upon, due to the high pressure exerted thereon when delivered into the final main indicated at 50. The emulsion here remains under pressure until discharged through the nozzle 51, that is, the pressure is instantly released or lowered when the emulsion discharges through the nozzle and it is thus permitted to explosively expand the moment released. An exceedingly efficient method of disrupting or breaking up the liquid fuel is in this manner obtained when it is considered that the globules are impregnated with air under exceedingly high pressure. The air disrupts with an explosive action when released and the water is also instantaneously disrupted. The fuel or oil particles are thus so finely divided that practically perfect combustion is permitted. Efficient combustion of any fuel, particularly liquid fuels, depends upon the degree of atomization obtained as combustion or burning of the particles cannot take place until the air or oxygen is supplied; hence the smaller the particles the greater surface area exposed and more rapid and thorough the combustion obtained.

30 The importance of first emulsifying the liquid fuel, then subjecting it to pressure, further emulsifying it and then increasing the pressure and maintaining the liquid under pressure until finally releasing it at a point where almost explosive expansion is permitted, should be obvious as all the steps are important when disrupting or breaking up of the fuel is considered.

35 While the present apparatus is more or less specific in design and construction, it is obvious that the invention is not limited thereto as various forms of apparatus may be employed, that is, any mechanism which is capable of first emulsifying the fuel, then exerting a pressure thereon, and finally releasing it so as to instantly lower the pressure, will accomplish the result desired.

40 To maintain the low pressure in the pipe line 28, which has heretofore been referred to as approximating 100 pounds, I employ a check valve such as indicated at 60. This check valve is identical to the by-pass valve indicated at 19, that is, the check is held on its seat by means of a spring and as the tension of the spring may be regulated, it

is possible to adjust the spring so that the check will not open until the pressure in the pipe 28 exceeds the pressure intended.

By referring to Fig. 2, it will be seen that 5 a second by-pass pipe is employed which connects the valve 60 with the by-pass pipe 20. This second by-pass pipe, which is indicated at 72, is of considerable importance 10 as it permits recirculation of a portion of the liquid through the first unit of the pump, that is, I have found in actual practice that it is desirable to slightly increase the capacity of the first three cylinders of the unit when comparison is made with the cylinders 15 in the second unit. The slight excess of liquid thus supplied is for this reason circulated over and over and materially increases the emulsifying action finally obtained.

20 Having thus described my invention, what I claim and desire to secure by Letters Patent is—

1. A method of preparing liquid fuels for combustion which consists in first mixing 25 the fuel with an expandible medium, secondly subjecting the mixture to a second emulsifying action, third, subjecting said emulsion to comparatively low pressure, fourth, again subjecting the mixture to further mixing 30 and emulsifying action, fifth, subjecting the final emulsion thus obtained to a high pressure, and sixth, instantly lowering the pressure before combustion to permit expansion and explosive disintegration by projecting 35 the emulsion into a chamber maintained under low pressure.

2. A method of preparing liquid fuels for combustion which consists in first forming an emulsion of the fuel by mixing the

fuel with an expandible medium, secondly, 40 subjecting the mixture to a second emulsifying action, third, subjecting the emulsion to a low pressure of approximately 100 pounds, fourth, again subjecting the mixture to a further emulsifying action, fifth, 45 subjecting the emulsion thus obtained to a high pressure, preferably in excess of 1000 pounds per square inch, and sixth, instantly lowering the pressure before combustion to permit 50 expansion and explosive disintegration by projecting the emulsion into a chamber maintained under low pressure when comparison is made with the high pressure mentioned.

3. A method of preparing a liquid fuel for 55 combustion, which consists first in impregnating the oil with air and subjecting the impregnated oil to pressure, secondly, subjecting the impregnated oil to a higher pressure, and third, instantly lowering the pressure 60 before combustion by projecting the emulsion into a chamber maintained under comparatively low pressure.

4. A method of preparing a liquid fuel for combustion, which consists, first, in impregnating the liquid fuel with air and water, secondly, subjecting the impregnated fuel to pressure, third, subjecting the impregnated fuel to an emulsifying action, 65 fourth, subjecting the emulsified fuel to a higher pressure than that to which the fuel was subjected during the first impregnating action, and fifth, instantly lowering the pressure before combustion by projecting the emulsified and impregnated fuel into 70 a chamber maintained under comparatively low pressure.

GEORGE L. FISH.
